DESIGN FOR A CANVAS RUBBER SOLED SHOE

John T. Crowley, Lambertville, N. J., assignor to
The Servus Rubber Company, Rock Island, Ill.,
a corporation of Illinois

Application September 6, 1949, Serial No. 4,868

Term of patent 7 years

(Cl. D7—7)

To all whom it may concern:

Be it known that I, John T. Crowley, a citizen of the United States, residing at Lambertville, in the county of Hunterdon, State of New Jersey, have invented a new, original, and ornamental Design for a Canvas Rubber Soled Shoe, of which the following is a specification, reference being had to the accompanying drawing forming a part hereof.

Fig. 1 is an elevation of one side of a canvas rubber soled shoe, showing my new design.

Fig. 2 is a front elevation thereof.

Fig. 3 is an elevation of the other side of the shoe shown in Fig. 1.

Fig. 4 is a rear elevation of the shoe.

Fig. 5 is a top plan view of the shoe.

I claim:

The ornamental design for a canvas rubber soled shoe, as shown.

JOHN T. CROWLEY.
